US00D685630S

(12) **United States Design Patent**
Birchmeier et al.

(10) **Patent No.:** **US D685,630 S**
(45) **Date of Patent:** **** Jul. 9, 2013**

(54) **BOWL**

(71) Applicants: **Kathryn M. Birchmeier**, Glenview, IL (US); **Seema Sundar**, Sun Valley, CA (US)

(72) Inventors: **Kathryn M. Birchmeier**, Glenview, IL (US); **Seema Sundar**, Sun Valley, CA (US)

(73) Assignee: **Kraft Foods Group Brands LLC**, Northfield, IL (US)

(**) Term: **14 Years**

(21) Appl. No.: **29/443,517**

(22) Filed: **Jan. 18, 2013**

Related U.S. Application Data

(62) Division of application No. 29/403,421, filed on Oct. 5, 2011, now Pat. No. Des. 678,050.

(57) **CLAIM**

The ornamental design for a bowl, as shown and described.

DESCRIPTION

FIG. 1 is a perspective view of a bowl, showing our new design;

FIG. 2 is a front elevational view of the bowl of FIG. 1, the rear elevational view being identical;

FIG. 3 is top plan view of the bowl of FIG. 1;

FIG. 4 is a right side elevational view of the bowl of FIG. 1, the left side elevational view being identical; and,

FIG. 5 is a bottom plan view of the bowl of FIG. 1.

The broken lines shown represent unclaimed subject matter and form no part of the claimed design.

1 Claim, 3 Drawing Sheets
